DESIGN FOR A GLOVE

Marinette Blanc, New York, N. Y., assignor to Fownes Brothers & Co. Incorporated, New York,
N. Y., a corporation of New York

Application April 7, 1938, Serial No. 76,350

Term of patent 3½ years

To all whom it may concern:

Be it known that I, Marinette Blanc, a citizen of the United States of America, and a resident of the Borough of Manhattan, city, county, and State of New York, have invented a new, original, and ornamental Design for a Glove, of which the following is a specification, reference being had to the accompanying drawing, forming a part thereof, and in which

Figs. 1 and 2 are plan views respectively of the front and back of a glove, showing my new design; and

Fig. 3 is a perspective view of the back of said glove as it appears when on the hand.

The characteristic feature of my design resides in the wrist and cuff portion of the glove.

I claim:

The ornamental design for a glove, substantially as shown and described.

MARINETTE BLANC.
